RADIO TUBE SOCKET

Donald Jackson, Cambridge, England, assignor to
 Pye Limited, Cambridge, England, a British
 company

Application July 25, 1946, Serial No. 686,170
 In Great Britain May 31, 1945

3 Claims. (Cl. 173—328)

1

This invention relates to improvements in electrical sockets. More especially, the invention relates to sockets for radio valves and the like, which sockets are commonly known as valve holders, although sockets of that character are often used also as holders for coils, condensers and other electrical equipment. The invention is more particularly concerned with the construction and manufacture of contact elements for such sockets, and with the manner of mounting and securing the contact elements in place therein.

In accordance with the invention, the contact element for a socket is made in one piece from metal strip and comprises two elongated strip pieces or limbs disposed side by side and integrally united between their ends by an integral bridge-piece, the two portions of the strip pieces which lie at one side of the bridge piece constituting or being made into a pair of springy tongues for receiving a cooperating contact pin, prong or blade on the base of a radio valve or other device, and the other portions of the strip pieces which lie at the other side of the bridge-piece being adapted, preferably respectively, for fixing the contact element in a socket and for effecting electrical connection to the contact element.

As indicated, it is preferred that the two latter portions be adapted to perform the stated functions separately. However, the possibility is not excluded of utilising the portion serving for effecting electrical connection to the contact element, to perform a fixing function as well. The portion serving for effecting electrical connection may be made longer than the corresponding portion of the other strip piece so as to form a suitable soldering or terminal tag for making electrical connection of a conductor to the contact element.

A socket embodying the invention has contact elements as described which are respectively housed and fixed in apertures provided in insulating material of the socket. For fixing a contact element in its aperture in the socket, the portion of the contact element which is adapted to serve for this purpose is preferably formed with a resilient part which is adapted to be compressed upon insertion of the contact element in its aperture so as to fix the contact element in position in the aperture by recoiling and latching of the resilient part, thus providing a construction of contact element which enables it to be self-fixed in the socket without requiring any further operation to secure it in place after insertion. The recoil part or latch may be formed by crimping the appropriate portion of the con-

2

tact element, or by striking up a latching tongue or projection from such portion, or by both crimping such portion and striking up a latching tongue or projection from the crimped portion.

5 In order that the invention may be more clearly understood and readily carried into practice, a preferred embodiment thereof will now be described with reference to the accompanying drawings, in which

10 Fig. 1 is a view in elevation and Fig. 2 is a side view, showing a preferred form of the improved contact element.

Fig. 3 is a view of the metal blank from which the contact element is formed, and

15 Fig. 4 is a fragmentary sectional view showing the contact fixed in its housing aperture in a socket.

In the embodiment illustrated, the improved contact element is made in one piece from a metal strip blank shown in Fig. 3, having a shape resembling the letter H, and comprising two lateral elongated strip pieces or limbs 1 and 2 joined by an intermediate bridge-piece 3. The contact element is formed by folding the limbs 1 and 2 about the ends of the bridge-piece so that the two limbs face each other, as seen in Fig. 1, the two portions 4 and 5 of the limbs which lie at one side of the bridge-piece 3 being shaped into a pair of springy tongues for receiving a cooperating contact pin, prong or blade on the base of a radio valve or other device, and the other portions 6 and 7 of the limbs at the other side of the bridge-piece 3 being adapted for fixing the contact element in a socket and for effecting electrical connection to the contact element. In the preferred form, as shown, the H-shaped blank has one limb 2 thereof longer than the other limb 1, the extended portion 8 of the longer limb constituting the terminal tag of the contact element

20 serving for making electrical connection thereto. The terminal tag 8 is shown as being formed with a usual notch 9 for facilitating the attachment and soldering of a connecting wire thereto. The portion 6 of the other limb 1 is crimped as shown

25 at 10 to form a resilient recoil part of the contact element which is adapted to be compressed upon insertion of the contact element in its housing aperture in a socket so as to fix the contact element in position in the aperture by recoiling and latching of the part 10, as will presently be explained. In the preferred construction, in addition to crimping the portion 10, a latching tongue 11 is struck up from such portion.

30 In order to avoid the transverse dimension 35 (as seen in Fig. 2) of the contact element being

increased at the region of the bridge-piece 3 by the thickness of the metal thereof, the blank is preferably made so that the two limbs 1 and 2 thereof are reduced in width at their region of union with the bridge-piece 3 by approximately the thickness of the strip material of the blank, as shown in Fig. 3, so that when the blank is folded, the bridge-piece 3 lies within the overall transverse thickness of the limbs of the contact element, as shown in Fig. 2.

The tips of the tongues 4 and 5 of the contact element are preferably suitably flared as shown for guiding the cooperating contact pin, prong or blade between them, and the tongues may also be suitably crimped or otherwise shaped as desired so as to provide points of line contact to ensure making a good conductive engagement with the cooperating pin, prong or blade.

The preferred form of contact element as illustrated is intended more especially for a socket having contact-receiving apertures therein which are formed with an enlarged portion communicating with a reduced portion of smaller bore, the contact element being accordingly formed with its pin-receiving part in the region of the bridge-piece 3 being stepped or flared out so as to be wider or enlarged compared with its remaining narrower part 6, 7, as seen in Fig. 1. The manner of mounting and securing the contact element in place in such a socket is illustrated in Fig. 4 in which 12 indicates a socket body of insulating material having contact-receiving apertures such as 13 extending therethrough, formed with an enlarged portion 14 at the face or topside of the socket (i. e. the side into which the contact pins, prongs or blades on the base of a radio valve or other device are inserted into the socket), the enlarged portion 14 communicating with a reduced portion 15 extending to the rear or underside of the socket body. The contact element is inserted, terminal tag end first, into the larger end of the aperture 13 and the terminal tag 8 and crimped part 10 pushed through the reduced portion 15 of the aperture so as to bring the pin-receiving tongues 4, 5 and the wider part of the contact element into the larger portion 14 of the aperture where they are accommodated and prevented from being drawn further through the aperture by reason of the reduced dimension of the portion 15. As the narrower end of the contact element is pushed through the reduced portion of the aperture 13, the crimped part 10 and latching tongue 11 are caused to be compressed or deflected inwards so as to pass through the reduced bore 15, the arrangement being such that when the tongues of the contact element reach their proper housed position in the enlarged portion 14 of the aperture, as shown in Fig. 4, the crimped part 10 and tongue 11 emerge from the reduced portion 15 of the aperture and are thereby enabled to recoil and latch the contact element in place. The latching tongue 11, having sprung out of alignment with the portion 15, as shown, forms a stop serving to hold the contact element against unintentional withdrawal from its housing aperture. The terminal tag 8 of the contact element projects from the rear or underside of the socket body 12, as shown, and can be bent as desired or convenient for making an electrical connection thereto.

The contact element and its aperture preferably cooperate to prevent the contact element from turning in the aperture. For this purpose, as the described contact element is of general

rectangular section in plan, the reduced portion 15 of its housing aperture 13 may be made of rectangular section conforming with that of the narrower part of the contact element, thus preventing the latter from turning. The larger portion 14 of the aperture may also be made of square or rectangular section conformably with the accommodated larger part of the contact element.

Improved contact elements in accordance with the invention may be utilised in various constructions of a valve holder or other socket having an insulating body provided with housing apertures suitable for accommodating this form of contact element, whether a single insulating body is provided housing all the contact elements of the socket in a series of apertures therein, or whether the insulating body of the socket consists of a plurality of separate apertured insulators in which the contact elements are housed individually or in groups. For example, the invention is especially applicable to valve holders and like sockets as described in the specifications of our applications Serial Numbers 546,501 and 586,603 which latter application has matured into Patent No. 2,453,014 dated November 2, 1948, in which the present improved contact elements may be embodied in place of those described in those specifications. Compared with those contact elements, the present form of contact element enables it to be fixed without involving a further operation of bending over parts of the contact element, and also the single-thickness terminal tag is more suitable for bending outwardly for soldering purposes than is the doubled loop form of tag of the previous contact elements.

I claim:

1. A contact element blank comprising a metal strip stamping having two lateral elongated limb portions united intermediate their ends by a bridge portion, said limb portions tapering in width along their inner edges towards said bridge portion so as to diminish the width of said limb portions at the region of their union with said bridge portion by an amount substantially equal to the thickness of the metal strip material of the blank.

2. A one-piece socket contact element comprising two elongated strips opposed face to face and integrally connected between their ends, at a region along one lengthwise edge of each strip, by a lateral resilient bridge-piece so that said strips are spaced apart at their region of connection with said bridge-piece by substantially the width of said bridge-piece, the two portions of said strips which lie at one side of said bridge-piece being of substantially equal length and being inwardly bent with their free ends outwardly turned to form a pair of resilient tongues supported by said bridge-piece whereby said tongues are adapted to be spread apart yieldably under their own resilience combined with the resilience of said bridge-piece by the insertion of a contact pin therebetween, the two portions of said strips which lie at the other side of said bridge-piece being of unequal lengths and substantially longer than said first mentioned two portions at said first-mentioned side of said bridge-piece, said unequal portions being inwardly bent to reduce their mutual spacing beyond their region of connection with said bridge-piece, the shorter one of said last-mentioned portions having a lateral tongue near its free end and extending outwardly in the direction of said bridge-piece to form a latch for releasably securing the contact element in an insulating carrier, and the longer one of

said last-mentioned portions forming a wiring tag for the contact element.

3. A contact element blank comprising a metal strip stamping having two lateral elongated limb portions united intermediate their ends by a bridge portion, the width of said limb portions diminishing along their inner longitudinal edges at the region of their union with said bridge portion by an amount substantially equal to the thickness of the metal strip material of the blank, said limb portions being of substantially equal length at one side of the bridge portion and being of unequal lengths at the other side of said bridge portion.

DONALD JACKSON.
